Inventor

UNITED STATES PATENT OFFICE.

GEORGE W. UPTON, OF WARREN, OHIO.

LIFE-PRESERVER.

1,269,982.

Specification of Letters Patent. Patented June 18, 1918.

Application filed June 1, 1914. Serial No. 842,268.

To all whom it may concern:

Be it known that I, GEORGE W. UPTON, a citizen of the United States of America, residing at Warren, in the county of Trumbull and State of Ohio, have invented certain new and useful Improvements in Life-Preservers, of which the following is a specification.

This invention relates to improvements 10 in devices for preventing persons from drowning, which devices have become generally known as life preservers; and is herein illustrated as embodied in a pole heavy at one end and buoyant at the other, though 15 it may be solid, or a tube or flexible.

The objects of my invention are first, to provide a device that will assist a person to float in water in such a way as to keep the head above the surface; second, will enable 20 a person to maintain a vertical position while in the water with feet down and head up; third, to provide a life preserver that will be effective without adjustment or explanation, and fourth, one that will be 25 cheap to make and require a minimum of room to store or carry on ships, boats, etc.

As heretofore constructed life preservers consist of implements lighter than water and made in the form of rings or floats to 30 be attached to one's body, or be fastened thereabout: many of them require inflation or other preparation and all ordinarily require adjustment and the manipulation of straps or fasteners requiring time and fore- 35 warning.

For my invention any suitable construction and arrangement which will produce the same or an equivalent mechanical and physical result may be used.

40 Those objects and other features of the invention will be described in connection with an illustrative device and pointed out in the appended claims.

In the accompanying drawings: Figure 45 1 is a diagrammatic view of the most simple form of my invention: Fig. 2 illustrates a modification and Figs. 3 and 4 illustrate addenda which may be used with convenience or for persons incapacitated by youth, 50 age, sickness or other causes.

As the human body in full life is of less specific gravity than water, and will not sink unless the air be expelled therefrom, it will float so long as it can be held in such

a position as to keep the breathing apparatus in the air and prevent the expulsion of the breath and air therefrom and admittance of water into the body in place thereof, as occurs when the feet rise because all the body below its normal center of gravity is lighter than water, and, in consequence, the head goes down and under the water causing the lungs to eject the air and permitting water to enter the mouth and nose.

Therefore my invention consists in an apparatus having a lower part of specific gravity greater than that of water, attached to an upper part of specific gravity less than that of water and of buoyancy preferably more than enough to support the entire apparatus with its upper part at the surface of the water.

The lower part may be seized by or be attached to the feet of the user and the upper part may be manually held or be attached to the upper part of the user's body.

Similar characters refer to like parts throughout the several views in which:—

A rod, 1, is attached at one end to a 80 weight 2 whose specific gravity is greater than that of water, and at the other end to a float 3, whose specific gravity is less than that of water, and whose buoyancy is sufficient to overcome the tendency of the 85 weight 2 to sink the apparatus as a whole.

Preferably the entire apparatus should have a buoyancy or lifting force something greater than the weight represented by that of the largest human body subtracted from 90 the weight of the water that body will if submerged displace, as a factor of safety.

By clasping the rod 1 with the feet near or resting on the weight 2, and holding the rod 1 so the float 3 is near the face or 95 slightly below it, the body will be held erect in the water: cannot sink and, with reasonable care, water can be kept from the nose and mouth: whereupon one can not drown while strength lasts to retain that position. 100 In Fig. 2 I have shown a flexible connection between the weight 2 and the float 3. In Fig. 3 I have shown at 4, 4', means for binding or strapping the feet (as of an invalid, a child or an unconscious person) to 105 the weight 2 and the upper trunk, chest, arms or neck to the float 3.

In Fig. 4 I have shown a basket or bag

like receptacle 5 for the feet, and loops for the arms 7, with a band 6 for the body.

All manners of securing the human body to the float and weight may be used without departing from my invention.

5 Wooden rods or tubes of any material or ropes, straps or cords may be used to connect the weight 2 to the float 3.

It will be seen at once that life preservers 10 constructed in accordance with my invention will occupy a minimum of space; will always be ready for instant use and will be so cheap to make that not to have at hand many more than the number of passengers 15 a ship may carry will be both inexcusable and unthought of; and that when people are beyond their depths in water, or accidentally go overboard, my life preservers can be thrown quickly and far and in such 20 quantities as to make their nonattainment practically impossible.

Copies of this patent may be obtained for five cents each, by addressing the "Commissioner of Patents, Washington, D. C."

I claim:

1. In a life preserver, the combination of a buoyant member adapted to float vertically consisting of a middle, connecting element, a float at the upper end and a weight at the lower end with means at the top and bottom for attachment of the user's arms or shoulders and feet respectively.

2. The combination in a life preserver of a buoyant member adapted to float vertically and consisting of a rod a float at the upper end and a weight at the lower end and capable of being retained in temporary attachment by and with the user's arms and legs respectively.

In testimony whereof I affix my signature in presence of two witnesses.

GEORGE W. UPTON.
